Application filed October 21, 1893. Serial No. 488,816. Term of patent 3½ years.

To all whom it may concern:

Be it known that I, CAROLINE K. HERRICK, a citizen of the United States, residing at East Orange, in the county of Essex, in the State of New Jersey, have invented and produced a new and original Design for Wall-Paper, of which the following is a specification.

The design consists of an arrangement of groups or branches of flowers and leaves of the "daffodil," tied by ribbons, and connected by ribbons having swinging bells attached thereto, as represented in the accompanying drawing. The border or upper portion of the design is also formed of groups or bunches of the same flowers and leaves, with festoons of

ribbons having swinging bells attached thereto, and an ornamental band composed of a row of ornaments formed of conventionalized daffodils as shown.

What I claim is—

1. The design for wall paper herein shown and described.
2. In the design for wall paper, the border herein shown and described.

Witness my hand this 16th day of October, 1893.
